UNITED STATES PATENT OFFICE

FREDERICK C. BRITTON, SR., OF PETERSBURG, INDIANA

FLUE OPENING STOP OR CLOSER

Application filed August 20, 1931. Serial No. 558,352.

This invention relates to devices for closing the stove pipe opening to chimney flues and relates particularly to a device of this character which is locked in position.

5 The primary object of the present invention is to provide a flue opening or hole closing device of the usual flat or plate like character which has associated therewith adjustable elements which are designed to engage 10 over the inner end of the chimney pipe opening to secure the cover plate firmly in position.

Another object of the invention is to provide a means for preventing heated gases, which are passing through the chimney, 15 reaching the outer end of the stove pipe opening where the cover plate is located, and thus damaging the wall surface through the heating thereof.

A still further object of the invention is to 20 provide a device of the character above described, in which the holding or securing means therefor may be readily manipulated, either for securing the plate in position or for releasing it, from the outside of the stove 25 pipe opening.

The invention will be best understood from a consideration of the following detailed description taken in connection with the accompanying drawing forming part of the 30 specification, with the understanding, however, that the invention is not confined to any strict conformity with the showing of the drawing but may be changed or modified so long as such changes or modifications 35 mark no material departure from the salient features of the invention, as expressed in the appended claims.

In the drawing, Figure 1 shows a vertical section through a portion of the wall adjacent the chimney flue, showing the device embodying the present invention in position 40 in a pipe opening leading to the flue.

Figure 2 is a sectional view taken substantially on the line 2—2 of Figure 1.

45 Referring now more particularly to the drawing, wherein like numerals of reference indicate corresponding parts in the views, the numeral 1 indicates a portion of a chimney wall through which is formed 50 a pipe opening 2 leading from within a room

to a chimney flue, the front wall of which is designated by the numeral 3. This pipe opening has the usual liner 4 therein which may be of metal or any other suitable fire resisting material such as terra cotta, or the like. The device embodying the present invention comprises a plate member 5, to the inner face of which are secured the relatively long resilient arms 6. Each of these arms, as shown in Figure 1, has its forward end turned to form an attaching terminal 7 which is riveted or otherwise suitably secured to the inner face of the plate 5, as shown. Each arm 6 is further formed to provide an arcuately formed forward portion 8 which merges into a straight rear portion 9 and terminates in an outwardly directed angular portion or finger 10. The portions 8 and 9 of each arm are joined through an abruptly outturned shoulder 11 and as shown the arms are so secured to the plate 5 as to have the convex surfaces of the arcuate portions 8 in opposed relation.

Mounted upon the arms 6 is a disk 12 which is of slightly less diameter than the interior diameter of the liner 4 which the plate 5 covers. This disk 12 has a pair of slots 13 formed therethrough on opposite sides of the center through which the arms 6 extend and at the central portion thereof is an aperture 14 over which is secured a nut 15, by means of a cap 16 which is riveted to the disk.

The central portion of the plate 5 is provided with an aperture 17, through which extends the relatively long screw 18. The outer end of the screw is provided with a slotted head 19 which bears against the outer face of the plate, while the inner end, which is threaded, passes through and has threaded connection with the nut 15 which is secured to the disk 12.

From the foregoing description, taken in connection with the accompanying drawing, it will be readily seen that upon rotating the screw 18 in the proper direction while pushing inwardly thereon, the disk 12 may be forced away from the plate 5 on the arms 6 and it will thus ride on to or against the shoulder portions 11 of the arms and thereby draw the free ends thereof together as

shown in dotted lines in Figure 1. The arms may then be extended into the pipe opening so as to position the plate 5 against the outer end thereof and to locate the free ends so 5 that when they are again allowed to move apart the portions 10 thereof will extend across the inner edge of the liner 4 in the manner illustrated. It will, of course, be readily seen that by reversely rotating the

10 screw 18, the disk 12 will be drawn out toward the plate 5 so as to bear against the forwardly curved portions 8 of the arms and thus cause the free ends to be forced apart. In addition to the function performed by 15 the disk 12 of actuating the arms when the screw 18 is rotated, it serves to prevent heat reaching the plate 5 and thus damaging the wall surface against which the plate bears.

20 By securing the plate 5 in position in the manner illustrated and described, it will be readily seen that back drafts through the chimney flue, no matter how violent, will not force the plate from position and thus cause the passage of smoke into the room 25 into which the chimney pipe opening opens. The plate 12 prevents the gathering of soot next to the outer cap and this prevents soot fires which are the cause of so many conflagrations. Furthermore, this plate 12 will 30 tend to prevent the plate 5 from being forced out of position by back firing.

Having thus described the invention, what is claimed is:

35 1. A chimney pipe opening cover comprising a plate adapted to cover one end of the opening, a pair of relatively long resilient arms each secured at one end to one face of the plate and each having its other end formed for engagement across the edge of 40 the opposite end of the opening, a shield disk disposed in spaced relation to said plate and slidably mounted on said arms and of a diameter to snugly close the opening, means connecting said disk with the plate whereby 45 the disk may be shifted relative to the plate, and means whereby the shifting of the disk will effect the flexing of the arms relative to one another, to move their free ends into position across an edge of the opening.

50 2. A chimney pipe opening cover comprising a plate, a pair of relatively long arm members each connected at one end to one face of said plate, each of said arms comprising an arcuate portion and a straight portion, said arcuate and straight portions of the arms being joined by an outwardly rounded shoulder, the arcuate portions of the arms being adjacent the plate and arranged with the convex surfaces in opposed 55 relation, the free end of each arm terminating in a laterally directed finger, a disk having apertures therethrough on opposite sides of the center through which said arms pass, the arcuate portions of the arms being positioned 60 in the disk apertures, a threaded nut secured 65

to the center of the disk and overlying an aperture therethrough, and a screw member extending through the center of said plate and through said nut, said screw being freely rotatable in the plate whereby the disk may 70 be shifted thereby on the arcuate portions of the arms relative to the shoulders thereof, to effect relative movement between the free ends of the arms.

75 3. A chimney pipe opening cover, comprising a plate, a relatively long screw extended through and rotatably mounted in said plate and having its inner end portion threaded, a disk disposed in spaced parallel relation to said plate and of a diameter to snugly close the opening, said screw having its threaded end extended centrally through said disk, means for threadably coupling the screw with the disk whereby rotation of the screw will effect the movement of the disk relative to the plate, and movable means for engaging the inner edge of the opening to secure the plate in position over the outer end thereof and shiftable to operative or inoperative position by the movement of said 80 disk.

85 In testimony whereof I hereunto affix my signature.
